UNITED STATES PATENT OFFICE.

FRANK MONTGOMERY, OF CENTRALIA, WASHINGTON.

SUSPENDED RAILWAY FOR CARRYING LOGS, &c.

1,128,029.

Specification of Letters Patent.

Patented Feb. 9, 1915.

Application filed June 11, 1914. Serial No. 844,440.

To all whom it may concern:

Be it known that I, FRANK MONTGOMERY, a citizen of the United States, residing at Centralia, in the county of Lewis and State of Washington, have invented certain new and useful Improvements in Suspended Railways for Carrying Logs, &c.; and I do hereby declare the following to be a full, clear, and exact description of the invention, such as will enable others skilled in the art to which it appertains to make and use the same.

My device relates to an elevated log railway system, and has as its object an arrangement whereby logs can be conveniently and quickly carried to a desired point by an arrangement that is strong, durable, yet simple and cheap in its structure.

With these and other objects in view to be developed as the specification proceeds, I will now proceed to explain my invention in which a preferred form is shown in the drawings attached hereto.

Similar characters refer to similar parts throughout the drawings in which,—

Figure 1, is a side elevational view of a preferred form of my invention. Fig. 2, an end view thereof. Fig. 3, end view of a modified form of structure. Fig. 4, end view of a still further modification.

Referring to Figs. 1 and 2 in the drawings 1 is my trestle structure comprising a pair of approximately vertical piles or upright supports 2 and 3 and a crown piece 35 or cross beam 4, said cross beam lying across the topmost ends of my uprights 2 and 3 and connecting them in pairs thereby.

Straddling the central portion of my cross beam 4 is a yoke member 5, said yoke member having a top portion 6 and two parallel side portions 7 and 8, thereby allowing the yoke 5 to neatly and snugly fit over the cross beam 4. In each end of the yoke 5 I strike an aperture or bolt hole through 45 which I run bolts in opposite directions, such as 9 and 10 in Fig. 1 of the drawings, these bolts being supported in the yoke member by means of ordinary nuts 11 and 12. These bolts support a single track member 13 running approximately through the central portion of said track member 13 as illustrated in Fig. 2 of the drawings, thereby letting room for my carriage device 14 to freely pass by, yet retaining track member against longitudinal displacement in either direction.

My carriage member 14 is composed of an approximately U shaped frame 15 having the usual cross piece and uprights 16 and 17, to the ends of which are attached spindles 18 and 19 respectively. 60

If desired, my carriage member 14 can be made of an open framework structure comprising in each instance a pair of upright bars 20 and 21 connected together from their top ends by cross member 22 and the spindles 23 and 24 can be mounted on each top corner or junction point as plainly shown in Fig. 1 of the drawings. Mounted upon my spindles 18 and 19, or 23 and 24, 70 are wheels 25 which are retained upon the spindles in any preferred manner.

Mounted in my upright structure 16 and 17 as shown in Fig. 2 of the drawings or by means of a member 26 as shown in Fig. 75 1 of the drawings, I mount, by means of suitable bearings 27 and 28, wheels 29. By this arrangement I have a device that will travel along the top surface of my track member 13, yet prevent it from scraping 80 against the track member by means of the wheels 29, which at the same time prevent lateral displacement of my carriage member 14.

Attached to my carriage member 14 as at 85 30 in Fig. 1 of the drawings, is a hook member which is attached to my carriage member 14, by means of bolts 31 and 32 or other suitable forms of fastening device. These hooks are placed in parallelism with each 90 other and upon opposite sides of my carriage member. I mount in these parallel hooks carrying chains 33 which support my logs 34, or other suitable freight or loads.

In the modification shown in Fig. 3 of 95 the drawings I retain my pulleys or upright supports 2 and 3 as in Fig. 1 or 2 of the drawings, together with the cross beam 1, but in this modification I use two yoke members 5 of the same construction as previously described, and from each yoke member by means of the bolt devices 9 and 10 I suspend track members 35 and 36, said track members being braced against lateral displacement by bracing members 37 and 38 as shown in Fig. 3, and in this double track arrangement I use as my carriage member 39 a U-shaped frame comprising connecting cross member 40 and uprights 41 and 42, being of the same structure as 110 previously described in my preferred form. Running across and through each member

41 and 42 are my axles 43 which have mounted on the ends thereof spindles 44 and 45 as shown in Fig. 3, and on each I mount in any preferred manner my wheels 5 46 and 47, these wheels reaching across the top surface of my track members 35 and 36 as shown. I also employ wheels 48 and 49 which are mounted the same as wheels 29 previously described, to retain my carriage 10 member 39 from lateral displacement and from scraping the surface of my track members 35 and 36. I attach my hook members 50 and 51 and supporting chain 52 as described in my preferred form said members being referenced as 30 and 33, my chain 52 likewise, in this instance, supporting a log or other desired load 53. In Fig. 4 of my drawings I still show another modification. In this instance my track members 20 54 and 55 being laid across the top ends of my supports 2 and 3, thereby doing away with the cross beam 1 as in the other forms shown and illustrated, and across the top surface of my track members 54 and 55 I 25 lay rails 56 and 57 upon which are mounted to travel my carriage device 58, which in this instance is composed of the substantially U-shaped member having a cross beam 59 and uprights 60 and 61 of the structure 30 as previously shown, and in this instance, braced by means of a cross brace member 62. My axle 63 mounting the spindles 64 and 65 is the form as shown and described in Fig. 3 of the drawings. My wheels 66 and 35 67, however, in this form of my device have interior and exterior flanges 68 and 69, these flanges playing along the side surface of my rails so that the said wheels will not roll off the rails. I also provide wheels 40 70 and 71 on my carriage member 58 to prevent lateral play or scraping of my track members 54 and 55. I also mount a plurality of hooks 72 which carry my supporting chains 73, the same as in the other 45 forms of my invention, these chains supporting and carrying logs 74 or other desired form of loads.

In operation, my elevated track system is constructed from the logging camp and runs 50 down the mountain or other elevation to the point where my logs are to be transhipped. I mount my logs on my device and allow gravity to transport them down the moun-

tain or if desired can use any preferred form of motive power. 55

What I claim as new and desire to secure by Letters Patent is:—

1. An elevated track system comprising a plurality of upright supports, cross members uniting said supports in pairs, track members suspended from said cross members, said track members being supported from said cross members by means of a yoke and oppositely disposed connecting means to prevent longitudinal displacement, an approximately U-shaped carriage having upright sides mounting wheels thereupon and carried by said track members, and means to support a load from said carriage member. 70

2. An elevated track system comprising, upright frame members, longitudinal track members supported from said upright members said supporting means consisting of a yoke member having angular ends with 75 apertures therethrough, and obliquely running and oppositely disposed bolts running in said apertures and connected to said track members to prevent longitudinal movement, and a load carrying carriage operated on 80 said track members, said load carrying carriage comprising an approximately U-shaped member, load supporting wheels mounted upon said U-shaped member and operating upon said tracks, and displacement wheels mounted in said U-shaped member, at right angles to and below the plane of said supporting wheels. 85

3. An elevated railway device comprising, elevated supports, yoke members having a 90 cross section and two parallel sections at right angles thereto, adapted to seat over said elevated supports, oppositely disposed and approximately crossed supporting means mounted in the ends of said yoke 95 member, a track member supported by said last mentioned means, and means to support a load and transport same over said track member.

In testimony whereof I have signed my 100 name to this specification in the presence of two subscribing witnesses.

FRANK MONTGOMERY.
